MACHINE FOR PRODUCING STAKE AND STRAND FABRICS.

Application filed November 22, 1924. Serial No. 751,518.

The present invention relates to apparatus for weaving a fabric of interlocked strands of non-flaccid material and is more particularly adapted for weaving fabrics of cane, reed, twisted paper, and similar materials.

One object of the present invention is to provide a simplified and improved machine for weaving fabrics consisting of closely spaced longitudinal strands interlocked by spaced stakes.

A further object of the invention is to provide a machine for weaving a variable pattern in a stake and strand fabric of cane, reed, or similar or equivalent material.

With these and other objects in view, the several features of the invention consist in certain novel features of construction, combinations and arrangements of parts hereinafter described and claimed, the advantages of which will be obvious to those skilled in the art from the following description.

In the accompanying drawings illustrating the preferred form of the invention, Fig. 1 represents a rear elevation with the frame partially in section of a machine embodying the features of the invention; Fig. 2 is a side elevation of the machine shown in Fig. 1; Fig. 3 is a detail illustrating guiding, shed forming and feeding mechanism with certain of the parts shown in section on the line 3—3 of Fig. 1; and Figs. 4 and 5 are details illustrating dissimilar patterns which may be formed throughout the length of a given fabric.

According to the present invention, a series of longitudinal strands are received in guide openings which are located in relatively close proximity to shed forming members. The shed forming members comprise upper and lower reciprocating bars, each of which is provided with a series of shed forming teeth adapted to engage and deflect the longitudinal strands. The guide member for the longitudinal strands is formed in two parts, which are relatively movable transversely of the fabric in a manner to vary the lateral position of predetermined longitudinal strands with relation to the shed forming members. In addition the shed forming members are actuated to engage and deflect the longitudinal strands in different planes. By virtue of this lateral shifting of the guide members, operat-

ing independently or coupled with a vertical shifting of the shed forming members, the character of the pattern may be varied throughout its length, as will be more particularly pointed out hereinafter. The fabric after its passage through the shed forming members and the insertion of a cross locking stake is fed longitudinally through yielding feed fingers.

Referring more particularly to the illustrated embodiment of the invention, the machine is provided with side bars 20 and 22, between which reciprocate upper and lower heads 24 and 26. Each of these heads is provided with a shed forming member 28 having a series of shed forming teeth 30 formed thereon, the spacing and configuration of the teeth corresponding to the size of the strand and the depth of the fabric to be formed. Positioned in advance of the shed forming members and cooperating therewith are guide bars 34 and 36, each bar being provided with a series of openings 38 and 40, indicated in Fig. 1, for the purpose of receiving and guiding successive longitudinal strands. The guide bars are independently mounted for transverse movement in cross heads 42 and 44 bolted between the side bars, as indicated. Each of the guide bars is provided with a tongue 46 received in a correspondingly shaped groove formed by the cross head and a detachable front bar 48. A transverse or lateral shifting movement of predetermined extent is imparted to the guide bars to vary the position of the longitudinal strands with relation to the shed forming members. The shed forming members are reciprocated at predetermined intervals to engage and deflect the strands by two sets of rotary cams indicated at 50 and 52 respectively. The cams 50 actuate the lower shed forming member through bell cranks 54 and links 57 connecting the bell cranks directly with opposite ends of the shed forming head. Each of the bell cranks is loosely journaled upon a cross shaft 56 and is retained in engagement with the actuating cam 50 through a spring 58. The upper shed forming member is reciprocated in timed relation to the lower member by the oppositely disposed cams 52, which are engaged by levers 60 also journaled upon the

shaft 56, as indicated in Figs. 1 and 3. The levers 60 are connected with rocker arms 62 through connecting rods 64. In addition, the rocker arms are connected directly with the shed forming members through short links 66. The rocker arms are journaled in the opposite ends of a cross shaft 68 mounted in the upper portion of the machine frame. By referring more particularly to Fig. 3, it will be observed that the projections on the upper and lower shed former actuating cams vary in height throughout a portion of the circumference of the cams. In forming the fabric indicated more particularly in Fig. 5, it will be observed that any given longitudinal strand 70 is deflected first above and then below successive cross stakes or strands 72. This is accomplished by moving the shed forming members toward one another into the same meeting plane for the formation of successive shed passages. For this purpose, projections 80 formed upon the upper and lower cams are of uniform height to impart a movement of uniform extent to the reciprocating shed forming members. If the pattern is to be formed as indicated in Fig. 4 with a longitudinal strand 82 extending lengthwise of the fabric in a straight line and a companion strand 84 deflected successively below and above both the strand 82 and cross locking strands 86, then the meeting plane of the shed forming members is shifted vertically for the formation of successive shed passages. This is accomplished by providing cam projections 86 and 88 formed upon the upper and lower cams respectively, the projections on each cam being successively high and low and alternating with low and high projections on the cooperating cam. This is indicated clearly in Fig. 3 where the cams 50 and 52 are shown one behind the other and in register. By virtue of this formation of the operating cams, the meeting plane of the shed forming members is located first above the plane of the straight longitudinals 82 and next below this plane. This method of operating the shed forming members produces a fabric having the general configuration illustrated in Fig. 4. In order to secure the proper deflection of the longitudinal strands with the reciprocating shed formers, it is necessary in addition to provide for a relative transverse movement of the strands and shed forming teeth. This is conveniently accomplished in the present mechanism by providing for a bodily lateral shift of the longitudinal strands with relation to the shed forming teeth. By virtue of this lateral shifting of the longitudinal strands, each longitudinal strand is successively engaged by adjacent shed forming teeth to deflect the strand first upwardly and then downwardly, as indicated clearly in Fig. 5.

In a like manner, this lateral shifting of the strands in conjunction with the vertical shifting of the shed forming members permits one set of strands to be passed through the shed forming members without deflection and the second set of strands to be deflected first above and then below the straight strand, as indicated in Fig. 4. The transverse movement of the guide bars 34 and 36 to shift the longitudinal strands is imparted by a shifting cam 90 journaled upon the side of the machine frame at 92 and having two cam paths 94 and 96 of identical shape and contour formed therein. Each of these cam paths is connected with one of the guide members through arms 98 and 100 respectively. In the illustrated embodiment of the invention, the upper and lower guide members are moved in unison to shift all of the longitudinal strands simultaneously in equal amounts. It will be evident to those skilled in the art, however, that if so desired the cam paths may be made of dissimilar shape to move the upper and lower guide members in opposite directions or in unequal amounts to impart a further variation to the fabric.

The shifting cams are actuated from the main drive shaft 102 through a sprocket wheel 104 driving a chain 106 and wheel 108 mounted on the shaft 92. The shed forming cams are mounted upon a cross shaft 110, which is continuously rotated from the main drive shaft through a driving pinion 112 meshing with a larger gear 114 mounted upon a shaft 116. This shaft carries a smaller gear 118, which in turn meshes with a gear 120 mounted on the cam shaft 110.

The fabric is advanced in a lengthwise direction between the formation of successive shed passages by upper and lower feeding fingers 121 and 122. Each set of fingers is in the form of comb teeth mounted upon thin bars or plates 124 which are slidably supported on upper and lower heads 126 and 128. The heads are mounted upon oppositely disposed swinging arms 130 and 132 pivoted at 134 and 136. The arms are moved in a direction to feed the fabric by operating levers 135 pivoted upon the side bars at 137 and engaged by cams 138. The upper end of each operating lever is provided with a slot 140, which receives a stud 142 projecting from the upper feed member 126. The lower feed member is connected thereto through a forked extension 144, which embraces each stud in a manner to cause the upper and lower feed combs to move in unison upon actuation of the operating levers. The shape of the teeth 121 and 122 is such that upon a forward feeding movement the upper and lower teeth engage behind a cross locking strand to feed the fabric, whereas upon a rearward movement the feed combs

are deflected relative to the fabric, causing the teeth to slide over the strand. This sliding movement of the feed combs is permitted through the pin and slot connection indicated at 150, a light spring 152 serving to normally maintain the combs in engagement with the fabric. Cooperating with the feed combs 120 and 122 are a second set of combs 160 and 162 which are intended to prevent displacement of the cross locking strand during the feeding movement by engaging with the longitudinal strands in advance of the cross locking strand. These retaining teeth are slidably mounted upon the heads 126 and 128. The teeth are furthermore provided with blunt rounded ends in order to prevent catching upon the strands during the retracting movement of the feed combs. From an inspection of Fig. 2 of the drawings, it will be observed that the feed cams 138 are provided with cam projections 151 and 153 of different heights in order to vary the feeding movement throughout the length of the fabric. This variation in the feeding movement between the formation of successive shed passages varies the distance between cross locking strands and modifies the surface appearance of the fabric. The feed cams 138 are continuously actuated from the gears 120 through smaller pinions 164 meshing with gears 166 connected to the feed cam.

The cross locking strand may be conveniently inserted by hand after the formation of the shed passage and during the time that the shed forming members are stationary. The cross locking strand is passed through the shed passage from an opening in one of the side bars in a manner which will be evident to those skilled in the art.

It will be evident from the foregoing description that a simple and efficient machine has been provided for the production of stake and strand fabrics and that the design of the machine enables the character and appearance of the fabric to be materially varied during the continuous operation of the machine.

While it is preferred to employ the specific construction and arrangement of parts shown and described, it will be understood that this construction and arrangement is not essential except so far as specified in the claims and may be changed or modified without departing from the broader features of the invention.

The invention having been described, what is claimed is:

1. A machine for producing stake and strand fabrics comprising cooperating sets of shed forming teeth, means for reciprocating the teeth toward and from one another at predetermined intervals, means for varying the meeting plane of the teeth to form successive shed passages in different planes,

means for guiding a series of parallel strands between the teeth to cause the formation of shed passages between the strands upon engagement by the teeth, and means for feeding the fabric after the insertion of cross strands in the shed passages thus formed. 70

2. A machine for producing stake and strand fabrics comprising cooperating sets of shed forming teeth, means for moving the teeth toward and from one another, means for guiding a series of parallel strands between the teeth, means for relatively moving the shed forming teeth and parallel strands in a lateral direction, means for varying the meeting plane of the teeth to form successive shed passages in different planes, and means for feeding the fabric. 75

3. A machine for producing stake and strand fabrics comprising cooperating reciprocating shed forming members, a series of shed forming teeth mounted upon each member, a guide member for directing a series of parallel strands between the shed forming teeth, means for shifting the guide member laterally between the formation of successive shed passages, means for varying the meeting plane of the shed forming teeth to form successive shed passages in different horizontal planes, and means for feeding the fabric. 80

4. A machine for producing stake and strand fabrics comprising shed forming teeth, means for moving the shed forming teeth toward one another to form a shed opening therebetween, means for guiding a series of parallel strands between the shed forming teeth, a feeding member engaging with the fabric beyond the shed forming teeth, and means for imparting a variable movement to the feeding member. 100

5. A machine for producing stake and strand fabrics comprising two sets of shed forming teeth, means for moving the teeth toward and from one another in timed relation, means for guiding a series of parallel strands between the teeth, feed fingers engaging with the fabric beyond the shed forming teeth, and means for imparting a variable movement to the feed fingers in timed relation to the movements of the shed forming teeth. 110

6. A machine for producing stake and strand fabrics comprising two sets of shed forming teeth, means for moving the teeth toward one another to form a transverse shed opening therebetween, means located in proximity to the teeth for guiding a series of parallel strands therebetween, means for imparting relative lateral movements to the guiding means and shed forming teeth between the formation of shed openings, and means for varying the meeting plane of the teeth in a manner to deflect predetermined lengthwise strands and maintain predetermined strands against deflection. 120

7. A machine for producing stake and strand fabrics comprising cooperating sets of shed forming teeth, means for moving the teeth toward one another to form a shed opening therebetween, cooperating guide members each engaging and guiding a series of parallel lengthwise strands, means for independently moving the guide members laterally, feeding means engaging with the fabric beyond the teeth, and mechanism for actuating the feeding means between the formation of shed openings. 35
8. A machine for producing stake and strand fabrics comprising upper and lower heads extending transversely, a series of shed forming teeth mounted upon each head, means for reciprocating the heads to form successive shed passages between the teeth, a guide member having a series of parallel guide passages formed therein, means for shifting the guide member laterally between the formation of shed passages, a feed comb adapted to engage with the fabric beyond the shed forming teeth, and means for actuating the feed comb to feed the fabric between the formation of shed passages. 40
9. A machine for producing stake and strand fabrics comprising cooperating shed forming teeth, a guide member having a series of guide passages positioned in proximity to the teeth and designed to guide parallel strands therebetween, a feed member positioned beyond the teeth, and means for actuating the shed forming teeth to form successive shed passages in different planes and vary the deflection of predetermined strands throughout the length of the fabric. 45
10. A machine for producing stake and strand fabrics comprising upper and lower heads, a series of shed forming teeth mounted on each head, means for guiding parallel strands between the teeth, means positioned beyond the teeth for feeding the fabric, rotary operating cams, and connections between the cams and each of the heads for reciprocating the heads in timed relation to form a series of successive shed passages in different planes. 50
11. A machine for producing stake and strand fabrics comprising cooperating shed forming teeth, means for moving the teeth toward one another to form successive shed passages therebetween, means for guiding a series of parallel strands between the teeth, upper and lower swinging arms, feed combs supported by the arms and designed to engage with the fabric, and means for actuating the arms in timed relation with the formation of the shed passages to feed the fabric between the formation of shed passages. 55
- 30 In testimony whereof I have signed my name to this specification. 60
